UNITED STATES PATENT OFFICE.

TIMOTHY J. COLLINS, OF TOLEDO, OHIO, ASSIGNOR TO RANSOM & RANDOLPH,
OF SAME PLACE.

DESIGN FOR A DENTAL CABINET.

SPECIFICATION forming part of Design No. 20,643, dated March 31, 1891.

Application filed January 19, 1891. Serial No. 378,358. Term of patent 14 years.

To all whom it may concern:

Be it known that I, TIMOTHY J. COLLINS, of Toledo, county of Lucas, and State of Ohio, have invented a new and original Design in 5 Dental Cabinets; and I do hereby declare that the following is a full, clear, and exact description of the invention, which will enable others skilled in the art to which it appertains to make and use the same, reference being had 10 to the accompanying drawing, and to the letters of reference marked thereon, which form part of this specification.

The drawing represents a perspective view of my newly-designed dental cabinet.

5 The leading feature of the design consists in a base 1, surmounted by a cabinet 2 of peculiar ornamental design. Cabinet 2 is of a width equal to the width of the base, and comprises a central rectangular portion 3 of slightly less depth than the depth of the base portion, the capital 4 being of the Ionic order and the front provided with panels 5, 6, and 7, the two latter being of bevel plate-glass. 10 Upon each side of the central portion 3 and

in rear thereof are paneled wings 8, extending to the outer edge of the base portion, each being formed with panels 9 and 10, respectively, the lower panels 9 being of a design to harmonize with panel 5 of the central portion and panels 10 arranged to give a pleasing effect to panels 6 and 7, there being a horizontal shelf 11 intermediate the panels 9 and 10 and provided with a fret-work 12. Surmounting each of the wings 8 and in rear thereof is an extension 13, ornamented with a scroll-work in flat relief, the whole design being of that character to give a pleasing effect.

What I claim is—

The design for dental cabinets herein described and shown.

In testimony that I claim the foregoing as my own I hereby affix my signature in presence of two witnesses.

TIMOTHY J. COLLINS.
